(57) **CLAIM**

The ornamental design for a Christmas tree bracket, as shown and described.

DESCRIPTION

FIG. 1 is a top perspective view of a Christmas tree bracket showing my new design;

FIG. 2 is a bottom perspective view thereof;

FIG. 3 is a front elevational view thereof, the rear elevational view is identical;

FIG. 4 is a left side view thereof, the right side view is identical;

FIG. 5 is a top plan view thereof;

FIG. 6 is an enlarged view thereof, taken from encircled portion 6 in FIG. 1;

FIG. 7 is an enlarged view thereof, taken from encircled portion 7 in FIG. 1;

FIG. 8 is an enlarged view thereof, taken from encircled portion 8 in FIG. 2;

FIG. 9 is an enlarged view thereof, taken from encircled portion 9 in FIG. 2;

FIG. 10 is an enlarged view thereof, taken from encircled portion 10 in FIG. 3;

FIG. 11 is an enlarged view thereof, taken from encircled portion 11 in FIG. 3;

FIG. 12 is an enlarged view thereof, taken from encircled portion 12 in FIG. 4;

FIG. 13 is an enlarged view thereof, taken from encircled portion 13 in FIG. 4;

FIG. 14 is an enlarged view thereof, taken from encircled portion 14 in FIG. 5;

FIG. 15 is a top perspective view of the Christmas tree bracket in a contracted state; and,

FIG. 16 is a bottom perspective view of the Christmas tree bracket in a contracted state.
